UNITED STATES PATENT OFFICE.

WILLIAM M. HOFFMAN, OF BUFFALO, NEW YORK, ASSIGNOR TO HOFFMAN PRODUCTS CORPORATION, OF BUFFALO, NEW YORK, A CORPORATION OF NEW YORK.

FUEL-OIL BURNER.

1,341,644.

Specification of Letters Patent. Patented June 1, 1920.

Application filed November 22, 1919. Serial No. 339,857.

To all whom it may concern:

Be it known that I, WILLIAM M. HOFFMAN, a citizen of the United States, residing at Buffalo, county of Erie, State of New York, have invented a certain new and useful Improvement in Fuel-Oil Burners, and declare the following to be a full, clear, and exact description of the same, such as will enable others skilled in the art to which it pertains to make and use the same, reference being had to the accompanying drawings, which form a part of this specification.

My invention relates to fuel oil burners and the process of operating the same. The object is to provide a simple, inexpensive fuel oil burner adapted to utilize the cheaper, heavier hydro-carbons and in which super-heated steam, volatilized hydro-carbon and oxygen are thoroughly mixed in order that a more nearly perfect combustion may result.

The device here shown is an improvement on devices described in several applications previously applied for by me on hydro-carbon burners of similar type.

Figure 1 is an elevation of the apparatus partly in cross-section.

f is a drip pan mounted on suitable supports, not shown in the drawing, and formed integral with or adapted to receive and support burner *h*. The drip pan *f* is provided with a circumferential air inlet opening *g*. The burner *h* is here shown in the form of an inverted cone with hollow wall or jacket *h*² which is angular in cross-section, such jacket *h*² is filled with an absorbent refractory material *j*, asbestos being suitable for this purpose. The outer wall of this jacket is pierced with outlet openings *i* in number as may be desired, and arranged in such manner as is thought suitable. The object is, irrespective of the particular form shown, to provide an oil trough in which the oil may be volatilized and burned as it escapes through the outlet ports *i*. The absorbent refractory substance carried in this trough will naturally serve to assist in the volatilization of the hydro-carbon used as fuel. Oil is supplied to this burner *h* from an oil reservoir *b*, communicating with said burner by means of a conduit *b*². The passage of oil through this conduit may be regulated by means of a valve *b*³. This inverted conical burner is provided with an axial passageway *g* therethrough, indicated at *h*³, which serves

as a mixing chamber for the products of combustion.

Disposed to project a jet of water vapor upward through this mixing chamber *h*³ is a nozzle *e* supplied with water vapor from a conduit *e*² which leads from a water vapor reservoir *d*. This nozzle is here shown as integral with the drip pan. It is apparent, however, the purpose would be as well served if the conduit *e*² were fitted with such nozzle at its lower extremity, such conduit being bent to direct the vapor jet in the manner here shown.

Superimposed over this burner *h* and spaced therefrom so as to provide an auxiliary passageway therebetween is a water vapor generating chamber *c*. This water vapor generating chamber *c* is in the form of a hollow, jacketed cylinder and the jacketed wall thereof, indicated as *c*², serves as the generating chamber proper. Chamber *c* is fixed to the burner *h* by means of bolts *b* and held in spaced relationship thereabove by means of spacer tubes *k*² which encircle these bolts and upon which the base *c*³ of the generating chamber rests. *a* is a water reservoir which communicates with the lower portion of the hollow wall *c*² of the vapor generating chamber *c* by means of a conduit *a*². The flow of water through the conduit *a*² may be regulated by means of a valve *a*³.

Located at a higher level than the water level in the water reservoir is a water vapor reservoir *d*. A vapor communicating means, indicated as *d*², is provided between the upper portion of the generating chamber *c*² and the vapor reservoir *d*. The conduit *e*² leads from the water vapor reservoir *d* to the nozzle *e*. The passage of vapor through this conduit may be regulated by means of a valve *e*³.

The method of operation is as follows:

To start the burner, oil is allowed to flow from the reservoir *b* to the trough *h*². A more highly volatile oil is placed in the drip pan and ignited. This serves to volatilize the heavier hydro-carbon seeping through the refractory absorbent filter in the oil trough and as it escapes through the ports *i* it is ignited. Water in desired quantity is admitted to the hollow jacket *c*² of the water vapor generating chamber *c* and as the same is vaporized, water vapor rises to the reservoir *d*. A head of steam is thus maintained in the water reservoir *a* as vapor communi-

cating means exist between reservoirs *a* and *d*. The valve *a*² may now be left open and water in desired quantity may be furnished the generating chamber. Through a conduit 5 *e*² water vapor is supplied to the nozzle *e* and from there projected into the mixing chamber *h*³ to there mix with the products of combustion.

It will be observed that in the construction of this apparatus an annular passageway has been provided intervening the outer wall of the burner and the inner surface of the drip pan. Through this annular passageway air is drawn from the air opening 10 *g* passing along the entire front of the burning jets emitted from the part holes *i*. This draft is increased by the action of the steam jet from the nozzle *e*. The burning hydro-carbon is thus mixed with oxygen while in 15 this passageway or auxiliary mixing chamber and this compound is further mixed when it enters the mixing chamber and mingles with the water vapor projected from the nozzle *e*. With good combustion the burning 20 should be most complete at the upper extremity of the chamber *h*³ where the products of combustion would burn with an intense blue flame.

It will be observed that in the method here adopted the oil trough in which the fuel is volatilized is almost completely encircled by the burning hydro-carbon and that the absorbent refractory substance therein contained, through which the oil must 35 pass, will increase the exposed surface per given quantity of fuel and delay the passage thereof so that volatilization will be most nearly complete. By virtue of the location of the air inlet with reference to the fuel 40 port holes *a* forced draft is created below the burning jets from such port holes which will draw the oxygen along their entire front so as to increase the quality of the combustion.

45 As the water vapor coming from the reservoir *d* would be more or less heavy with condensed vapor particles, this vapor is superheated before it reaches the nozzle by having the conduit leading thereto so disposed with reference to the combustion chamber that the heat in such chamber will superheat the vapor in the conduit. This is 50 accomplished in the device illustrated in the drawing by passing the conduit directly 55 through the combustion chamber.

Claims:

1. In a device of the class described, an inverted conical drip pan, an inverted, conical, hollow, jacketed oil burner with perforated 60 outer wall concentric with said drip pan, and carried therein and supported thereby, so as to provide an annular chamber therebetween, an air inlet opening at the upper extremity of said chamber, a nozzle so disposed in the lower portion of said chamber,

beneath said oil burner, as to draw an air draft along the outer wall of said burner and to project a vapor jet into the hollow interior of such burner, means for supplying water vapor to such nozzle, and means 70 for supplying oil to such oil burner.

2. In a device of the class described, a hollow, jacketed oil burner with perforated outer wall disposed within a drip pan and spaced therefrom so as to provide an annular chamber between the outer wall of such oil burner and the wall of such drip pan, an air inlet opening in such drip pan above the 75 perforated outer wall of such burner, means for projecting a jet of vapor into the hollow interior of such burner, such means so located as to produce an air draft along the entire front of the perforated face of the oil burner and to force the products of combustion upward into the hollow interior 80 thereof, means for supplying water vapor to such vapor projecting means, means for supplying oil to such oil burner.

3. In a device of the class described, a hollow, jacketed oil burner with perforated outer wall, an oil drip pan encircling the same and providing an annular chamber therebetween along the front of said perforated wall, said annular chamber opening at the top to provide an air inlet, vapor projecting means so disposed in the lower portion of such annular chamber as to project vapor upward into the hollow interior of such oil burner and so located with reference to the air inlet opening to such annular 95 chamber as to draw an air draft there-through along the entire front of said perforated wall and to force the products of combustion upward into the hollow interior of such burner, means for supplying water 100 vapor to such vapor projecting means, means for supplying oil to such oil burner.

4. In a fuel oil burner a hollow, jacketed, inclosed oil trough, the outer wall of which is perforated, an absorbent refractory filler 110 for such oil trough, a drip pan adapted to encircle such oil trough and spaced therefrom so as to provide an annular chamber therebetween along said perforated wall, an air inlet opening at the top of said annular chamber, vapor projecting means so disposed in the floor of such drip pan as to draw an air draft through such air inlet opening at the upper portion of said annular chamber along the perforated wall of 115 said oil trough and force the products of combustion upward into the hollow interior of such oil trough, means for supplying oil to such oil trough, means for supplying water vapor to such vapor projecting 120 means.

5. In a device of the class described, a hollow oil burner provided with an outwardly perforated, jacketed wall, adapted to serve as an oil trough, a drip pan adapted to 130

- receive such oil burner and so spaced therefrom as to provide an annular chamber therebetween along said perforated wall, an air inlet opening at the top of said annular 5 chamber, vapor projecting means so disposed as to project a vapor blast into the hollow interior of the oil burner and so positioned with reference to the air inlet opening and the perforated wall of said oil 10 trough as to draw a draft of air along the entire front of said perforated wall, means for supplying oil to said oil trough, a hollow, jacketed cylinder adapted to serve as a vapor generating chamber superimposed 15 over said burner, means for supplying water to said generating chamber, a water vapor reservoir located at a higher level than the water level in said water supplying means of said generating chamber, communicating 20 means between said vapor generating chamber and said vapor reservoir, communicating means between said vapor reservoir and said vapor projecting means.
6. In a device of the class described, a 25 hollow oil burner provided with an outwardly perforated jacketed wall adapted to serve as an oil trough, a drip pan adapted to receive such oil burner and spaced therefrom so as to provide an annular chamber 30 therebetween along said perforated wall, an air inlet opening at the top of said annular chamber, a nozzle so disposed in the floor of said drip pan as to project a jet of vapor upwardly into the hollow interior of said oil 35 chamber and so disposed with reference to said perforated wall of said oil trough and said annular chamber as to draw an air draft along the front of said perforated wall and to force the products of combustion 40 upwardly into said hollow interior of said burner, a hollow, jacketed, cylinder of greater interior diameter than the diameter of the interior of said burner superimposed over said burner; an elevated water reservoir, communicating means between said 45 water reservoir and the jacketed wall of said cylinder, a water vapor reservoir located at a higher level than the water level in said water reservoir and provided with communicating means therewith, communicating means between said water vapor reservoir and the jacket of said cylinder, a communicating conduit between said water vapor reservoir and said nozzle, said conduit so disposed with reference to the burner 50 that the vapor passing therethrough will be superheated before it reaches the nozzle.
7. In a device of the class described, a hollow, jacketed oil burner with perforated outer wall, an oil drip pan encircling said burner and providing an annular chamber therebetween along the front of said perforated wall, said annular chamber opening at the top to provide an air inlet, vapor 60 projecting means so disposed in the lower portion of said annular chamber as to project vapor upward into the hollow interior of such oil burner and so located with reference to the air inlet opening of such annular chamber as to draw an air draft there- 65 through along the entire front of said perforated wall and to force the products of combustion upward into the hollow interior of such burner, a steam generating chamber superimposed over said burner, a water 70 reservoir, water communicating means between said reservoir and said steam generating chamber, a water vapor reservoir located at a higher level than the water level of said water reservoir and communicating 75 therewith, communicating means between said steam generating chamber and said vapor reservoir, a conduit between said vapor reservoir and said vapor projecting means, said conduit passing through the hol- 80 low interior of said burner.
- In testimony whereof I sign this specification.

WILLIAM M. HOFFMAN.
